UNITED STATES PATENT OFFICE.

JOHN WINSOR, OF CORRY, PENNSYLVANIA.

WIRE-BENDING MACHINE.

1,273,020.

Specification of Letters Patent. Patented July 16, 1918.

Application filed May 17, 1916. Serial No. 98,110.

To all whom it may concern:

Be it known that I, JOHN WINSOR, a citizen of the United States, residing at Corry, in the county of Erie and State of Pennsylvania, have invented certain new and useful Improvements in Wire-Bending Machines, of which the following is a specification, reference being had therein to the accompanying drawing.

10 This invention relates to wire bending machines and is an improvement upon Patent #1,113,104, dated October 6, 1914, issued to John R. Dean, the object being to provide a double guideway in order to form a two-point suspension for the shuttles, whereby friction will be reduced as the shuttles are supported in the guideway in such a manner that the same can be driven with less power.

Another object of my invention is to provide a wire bending machine in which the shuttles are mounted between spaced plates having guideways formed therein in such a manner that the wire carried by the bobbins of the shuttles will be prevented from getting tangled in the gearing when the wire accidentally breaks, thereby overcoming the disadvantages now existing in machines of this character.

Another object of my invention is to provide a wire bending machine in which a pair of figure-8 guideways are employed in which the bearings of the shuttles are mounted in such a manner that the shuttles are supported in the guideways so as to eliminate the drag of the shuttle when being driven by the driver, as is the case of wire bending machines now in use in which a shuttle travels in a single guideway.

Another object of my invention is to provide a wire bending machine in which the carrying capacity of the bobbins can be increased by supporting the shuttles at two points thereby saving the time of refilling the bobbins of the shuttles.

45 Another and further object of my invention is to provide novel means of constructing the guideways by supporting the central plates forming the inner edges of the guideways in such a manner that they will be supported in the proper position without interfering with the driving of the shuttle driver or the movement of the shuttle of the guide-

Another and further object of my invention is to provide an improved construction 55 of driver by forming the same of a driving sleeve provided with a pair of disks having notches adapted to receive trunnions of the shuttles so as to obtain a two-point contact drive for the shuttle in order to carry the 60 same through the guideways in such a manner that friction is greatly reduced.

Another and further object of my invention is to provide a wire bending machine 65 in which a greater number of shuttles can be employed in connection with the figure-8 guideways so as to form a multiple wire stay.

Other and further objects and advantages of the invention will be hereinafter set forth and the novel features thereof defined by the 70 appended claims.

In the drawings,

Figure 1 is a longitudinal vertical view, partly in section, of my improved construction of wire bending machine.

75 Fig. 2 is a top plan view of the same.

Fig. 3 is a section through the shuttle showing the position of the same and the double driver and the double guideway.

Fig. 4 is a perspective view of the driver, 80 the driving disks being removed from the driving sleeve.

Fig. 5 is an elevation of the figure 8 guideway showing the drivers and shuttles.

Fig. 6 is an enlarged detail section taken 85 on the line 6—6 of Fig. 2, and

Fig. 7 is a plan view of a portion of an article formed by the machine.

Like numerals of reference refer to like parts in the several figures of the drawing.

In carrying out my invention, I employ a base plate 1 mounted on legs 2 which are preferably provided with bearings 3 in which a driving shaft 4 is mounted having a drive pulley 5 at one end and a gear 6 which 95 extends upwardly through a slot formed in the base plate 1 and is adapted to drive the shuttle drivers of the machine through the medium of gears as will be hereinafter fully described.

100 Mounted on the base plate 1 at one end, are a pair of standards 7 preferably bolted to the base plate, as shown, each standard being provided with a pair of apertured heads 8 and 9 which are adapted to aline 105 with one another, and in which are ar-

ranged non-rotating bearing shafts 10 and 11, fixed in position with the aperture of the heads by set-screws 12.

5 Mounted on the bearing shaft 11 is a gear 13 which meshes with the gear 6, and carries a gear 14 which meshes with a gear 15 carried by the bearing shaft 10 as clearly shown in Fig. 2. By this construction as the shaft 4 is driven by the pulley, the gears 14 and 15 are revolved through the driving connection with the gears 6 and 13 which construction is substantially the same as shown and described in the Dean patent 10 above referred to.

15 Mounted on the opposite end of the base plate 1 are spaced guide plates 16 and 17 which are provided with base portions adapted to be bolted to the base plate 1 as clearly shown in Figs. 1 and 2, each plate 20 being provided with a cut-out portion to form the outer peripheral edge of a guideway 18 which is substantially the shape of a figure 8.

The ends of the bearing shafts 10 and 11 extend through the guide plates 16 and 17 and secured on the outer ends of these shafts are plates 19 and 20 forming the inner edges of the guideway 18 of the guide plates 16 and 17. The hub portions 19' and 20' receive 30 the shafts 10 and 11, and are secured in position upon said shafts by pins 21 passing through the hub portion and shafts as shown in Fig. 5.

25 The central guide-plates 22 and 23 forming the inner edge of the guide-way 18 of the guide plate 16 are provided with annular flanges 22' and 23' on their outer faces which are adapted to be seated in reduced portions 24' and 25' of bearings 24 and 25, carried by a standard 26 bolted to the base as shown in Fig. 1, said central guide plates being secured to the bearings by bolts 27 as 40 shown for securely holding the central guide-plates in their relative position in respect to the outer edge of the guide-way formed by the cut-away portion of the guide plate 16.

50 Mounted loosely on each of the bearing shafts 10 and 11 within the bearings 25 and 24 are driving sleeves 28 and 29, the driving sleeves 29 being keyed within the hubs of the gears 13 and 14 so as to rotate therewith, and the driving sleeve 28 being keyed within the hub of the gear 15 so as to rotate there- 55 with, said bearing sleeves extending loosely through the central guide-plates 22 and 23 and terminating adjacent the hub portions 19' and 20' of the central guide plates 19 and 20.

60 The drive sleeves 28 and 29 are formed identically alike and the description of one is sufficient for both, each sleeve having adjacent its outer end a pair of annular apertured flanges 30 against which are adapted 65 to be secured by bolts, disks 31 and 32 having

their peripheral edges notched as shown at 33 forming spaced drivers which are adapted to engage the trunnions of the shuttles for carrying the shuttles through the guideway as will be hereinafter fully described.

70 From the construction thus far described, it will be seen that I have provided a wire bending machine in which a pair of spaced guideways are arranged on the base plate having a pair of drivers mounted between the guideways in such a manner as to coöperate with the shuttles mounted in the guideways as will be hereinafter fully described, each driver being driven from the driving gear of the machine in such a manner that the central guide plates forming the inner edges of the guideways are supported independent of the driving sleeves so as to allow the drivers to rotate freely in such a manner as not to interfere with the movement of the 80 shuttles in the guideways.

85 In the construction of a wire bending machine herein shown, provision is made for employing five shuttles, as each driver, which is composed of a pair of driving disks, is provided with five notches so as to coöperate with the shuttles; and in Fig. 5 I have shown five shuttles in position within the guideway, which shuttles are adapted to be forced through the guide-way so as to 90 traverse the figure-8 guideway, and thus wrap the wire alternately around the pins 34 in substantially the same manner as shown and described in the Dean patent 95 above referred to.

100 My improved construction of shuttle comprises a casing 35 having means for supporting a bobbin 36 carrying the wire 37 therein, said casing having oppositely disposed trunnions 38 and 39 which are provided with antifriction rollers 40 to receive the drivers in order to cause the shuttles to move in the guideways as will be hereinafter 105 fully described.

110 The trunnions 38 and 39 are provided with guide-plates 41 and 42 from which are spaced guide-plates 43 and 44 by pins 46 and 47 carrying antifriction rollers 48 adapted to travel in the guide-ways of the plates 16 and 17 in order to form a two-point suspension for the shuttle so as to allow the same to be driven freely through the guideways without any drag caused by the sagging of the shuttle, from the weight of the bobbin mounted therein, and I have found 115 by experimenting that by employing a two-point suspension for a shuttle, the amount of wire carried by the bobbin can be greatly increased in order to allow the machine to be operated to produce a greater number of 120 stays without refilling the bobbins.

125 The trunnion 38 is provided with a central bore forming an opening through which the wire 37 passes from the bobbin, said wire extending through an opening formed 130

in the outer guide-plate 43 from which it passes to the tension wheel 47' upon which it is wrapped a sufficient number of times to prevent any slipping. The wire then 5 passes from the tension wheel 47' which is constructed in any desired manner between grooved pulleys 48' to the pins of the guide-plates.

From the foregoing description, it will be 10 seen that I have improved the general construction of the Dean patent by providing the machine with a pair of double figure-8 guideways between which a number of shuttles are suspended in order to obtain a two-point suspension for each shuttle so that the 15 weight of the shuttle and wire carried by the bobbin within the same will be supported at two points, which increases the life of the bobbin and allows the same to run freely 20 through the figure-8 guideway. It will be seen that I have improved the general construction of driver by providing a driver formed of spaced notched disks which are adapted to engage the trunnion of the shuttle 25 casing, at each side, between the suspension points so as to carry the shuttle through the guideway in such a manner that friction is greatly reduced. It will also be seen that I have arranged the shuttles between guide 30 plates forming the guideway in such a manner that the guide plates form guards so as to prevent the wire which may become accidentally released from the bobbin from becoming entangled in the gear of the machine.

35 I claim:

1. In a wire bending machine, the combination with a pair of opposing spaced parallel guideways, of a plurality of shuttles suspended in said guideways, and drivers 40 engaging the shuttles for causing the said shuttles to traverse said guideways.

2. In a wire bending machine, the combination with a pair of opposing spaced figure-8 guideways, of a plurality of shuttles 45 suspended in said guideways, and drivers having two-point contacts with said shuttles for causing said shuttles to traverse said guideways.

3. A wire bending machine, comprising a 50 pair of opposing spaced figure-8 guideways, a plurality of shuttles suspended between said guideways and adapted to traverse said guideways, and drivers comprising spaced members engaging said shuttles at each side 55 of the bobbin casing thereof.

4. A wire bending machine, comprising a 60 pair of horizontally disposed shafts, spaced guide plates having cut-out portions arranged around said shafts, plates arranged over the end portions of said shafts forming the inner edges of figure-8 guideways formed by the cut-out portions of said guide plates, shuttles arranged between said guide plates having guide members slidably 65 mounted within the guideways of said guide

plates, and drivers mounted on said shaft comprising spaced members contacting with said shuttles adjacent each guide plate.

5. In a wire bending machine, the combination with a pair of spaced guide plates 70 having openings for forming the outer edges of a pair of figure-8 guideways, central plates for forming the inner edges of the guideways, shafts carrying the central plates of one of said guideways, bearings for said 75 shafts carrying the central plates of the other guideways, driving sleeves loosely mounted in said bearings on said shafts, drivers carried by said driving sleeves, and shuttles suspended between said guide plates 80 having guide members mounted in the guideways thereof and adapted to be driven by said drivers.

6. In a wire bending machine, the combination with a pair of opposing spaced guide 85 plates having openings for forming the outer edges of a pair of figure-8 guideways, central plates for forming the inner edges of said guideways, shuttles arranged in the 90 guideways, and revoluble drivers having two-point contacts with said shuttles to cause said shuttles to traverse said guideways.

7. In a wire bending machine, the combination with a pair of opposing guide 95 plates having openings for forming the outer edges of figure-8 guideways, central plates for forming the inner edges of said guideways, shafts for centering said plates, shuttles arranged between said guide plates 100 and having two-point suspension in said guideways, drivers revolubly mounted on the shafts coating with said shuttles, and means for revolving said drivers.

8. A wire bending machine, comprising a 105 base plate having a pair of horizontally disposed shafts mounted thereon, driving sleeves mounted on said shafts, a driving connection between said sleeves, drivers carried by said driving sleeves, a pair of opposing spaced guide plates having guideways surrounding said shafts, and shuttles suspended in said guideways adapted to be actuated by said drivers.

9. A wire bending machine having a pair 115 of supporting shafts, driving sleeves revolubly mounted upon said shafts, a driving connection between said sleeves, bearings for supporting said shafts and sleeves, a pair of guide plates having cut-out portions through which said shafts extend, guide plates carried by the ends of said shafts forming a figure-8 guideway in the outer guide plate, and guide plates carried by said bearings forming a figure-8 guideway in the inner guide plate.

10. In a wire bending machine, the combination with a pair of spaced opposing plates, each plate having a substantially 120 figure-8 guideway, one of said plates hav-

ing forming pins at the crossing of said guideway, shuttles arranged between said guide plates and having guide members traveling in said guideways, and drivers arranged between said guide plates for actuating said shuttles to carry the wire from said shuttles alternately around said pins.

11. In a wire bending machine, the combination with a pair of opposing spaced 10 guide plates having guideways, of shuttles having guide members slidably mounted in said guideways for suspending said shuttles between said guide plates, and a driver formed of spaced members contacting with 15 said shuttles to cause said shuttles to move in said guideways.

12. In a wire bending machine, the combination with a pair of opposing parallel plates having guideways, of shuttles provided 20 with trunnions having guide members slidably mounted within said guideways, and a driver comprising a pair of driving members adapted to engage said trunnions for causing said shuttles to move 25 in said guideways.

13. In a wire bending machine of the class described, the combination with a pair of opposing guide plates having guideways, of a shuttle arranged between said guideways 30 comprising a casing having oppositely disposed trunnions carrying guide members slidably mounted within said guideways for suspending said shuttle between said guide plates, a driving sleeve, and a pair of disks 35 fixed on said sleeve having notched edges coacting with said trunnions for causing said shuttles to move in said guideways.

14. In a wire bending machine, the combination with a pair of supporting shafts, 40 of a pair of guide plates provided with openings arranged over said shafts, a guide plate carried by the end of each said shaft forming a guideway in the outer guide plate, a driving sleeve revolvably mounted on said 45 shaft, a bearing for said sleeve, a guide plate fixed to said bearing forming a guideway in the inner guide plate, a gear fixed on said driving sleeve, shuttles provided with oppositely disposed trunnions carrying guide 50 members mounted in said guideways, and driving disks fixed on said driving sleeve between said guideways having notched edges to receive said trunnions for causing said shuttles to move in said guideways.

15. In a wire bending machine, the combination with a base plate having standards 55 mounted thereon provided with apertured heads, of parallel shafts fixed in said heads, driving sleeves revolvably mounted upon said 60 shafts, gears carried by said sleeves, a pair of guide plates having openings mounted upon said base over said shafts, guide plates carried by the ends of said shafts forming a substantially figure-8 guideway in the outer 65 guide plate, bearings for said driving sleeves,

guide plates connected to said bearings forming a substantially figure-8 guideway in the inner guide plate, shuttles provided with oppositely disposed trunnions terminating in guide members mounted in the guideways of said guide plates, and notched disks forming drivers coacting with the trunnions of said shuttles for causing said shuttles to move in said guideways.

16. In a wire bending machine, the combination with spaced opposing guide plates, each guide plate having a substantially figure-8 guideway formed therein, of a plurality of shuttles arranged between said guide plates, each shuttle having oppositely disposed trunnions terminating in guide members mounted within the guideways of said plates, and spaced driving members revolvably mounted between said guide plates coacting with the trunnions of said shuttles for causing said shuttles to move in said guideways.

17. In a wire bending machine, the combination with a pair of horizontally disposed shafts, of opposing parallel guide plates disposed over said shafts provided with substantially figure-8 guideways, driving sleeves revolvably mounted upon said shafts provided with spaced flanges, spaced disks fixed on said sleeves against said 95 flanges forming two-point contacts, and shuttles having guide members slidably mounted within said guideways actuated by said drivers.

18. In a wire bending machine, the combination with a pair of opposing spaced figure-8 guideways, of a pair of revolvable drivers mounted between said guideways, each driver having two-point contacts, and shuttles having guide members mounted within 105 said guideways and suspended between said guide plates, said shuttles being actuated by said drivers causing said shuttles to traverse said guideways.

19. A wire bending machine having a pair 110 of opposing spaced guideways, a plurality of shuttles slidably mounted in said guideways forming a two-point suspension therefor, and drivers formed of spaced members formed of two-point contacts for said shuttles.

20. In a wire bending machine, the combination with a pair of opposing guideways, of shuttles mounted in said guideways, said shuttles being provided with oppositely disposed trunnions carrying guide members forming a two-point suspension for said shuttles, and driving members formed of spaced notched disks coacting with the trunnions of said shuttles for causing said shuttles to move in said guideways.

21. In a wire bending machine, the combination with a pair of opposing spaced guideways, of a plurality of shuttles mounted in said guideways and suspended between said 130

guideways, each shuttle comprising a casing adapted to receive a bobbin, and provided with oppositely disposed trunnions carrying guide members traveling in the guideways, 5 and drivers composed of spaced notched disks coöperating with the trunnions for causing said shuttles to move in said guideways.

22. In a wire bending machine, the combination with a pair of opposing spaced guide plates, each guide plate having a guideway formed therein, of a shuttle adapted to travel in the path of said guideway, said shuttle comprising a casing having oppositely disposed trunnions provided with guide members traveling in the guideways, and two-point contacts, coöperating with the trunnions of said shuttle. 10

23. In a wire bending machine, the combination with a pair of spaced opposing guide plates, each guide plate being provided with a substantially figure-8 guideway, of a pair of spaced drivers disposed between said guide plates, each driver comprising a pair of spaced disks, a driving sleeve upon which said disks are mounted, means for driving said sleeve, and a plurality of shuttles having oppositely disposed trunnions adapted to be engaged by 25 said driving disks and provided with guide members traveling in the guideways of said guide plates. 30

24. In a machine of the character described, a front figure-8 guideway, a rear figure-8 guideway arranged in spaced relation to said front guideway, the axes of the loops of said rear guideway being in alignment with the axes of the loops of said front guideway, a spool carrier mounted in the 35 space between said front and rear guideways, and means operating between said front and rear guideways for causing said spool carrier to traverse said guideways, substantially as set forth. 40

45 25. In a machine of the class described, a front figure-8 guideway, a rear figure-8 guideway arranged in spaced relation to said front guideway, the axes of the loops of said rear guideway being in alignment with the axes of the loops of said front guideway, a plurality of spool carriers mounted in the 50 space between said front and rear guideways, a rotating spool-carrier actuating-mechanism operating in the space between said front and rear guideways and engaging said 55 spool carriers to cause them to traverse said guideways, substantially as set forth.

26. In a machine of the class described, a

base plate, a front and rear guide-plate thereon having figure-8 raceways thereon, 60 said rear guide-plate having openings at the axis of each loop of said raceway, a hollow shaft in each of said openings, a pair of spaced disks on each of said hollow shafts between said guide-plates having coincident 65 radial slots in the peripheries thereof, journal bearings secured upon said base plate to support said hollow shafts, spur gears non-rotatably secured upon each of said hollow shafts, a pair of non-rotatable shafts extending through said hollow shafts, means to non-rotatably support the rear end of each of said non-rotatable shafts, a plate secured upon the front end of each of said non-rotatable shafts, a coil-forming pin supported by 70 each of said plates over the central portion of the figure-8 raceway in said front guide-plate, a shuttle in each of said raceways, a spool-carrier having an opening leading therefrom through the shuttle in the front 75 raceway supported between said shuttles and adapted to enter one of said radial slots in each of said disks, and gear and shaft mechanism to cause said spur-gears and disks to rotate in opposite directions, substantially 80 as set forth.

27. In a machine of the class described, a spool-carrier mechanism, supporting studs on opposite sides thereof, a raceway plate in front of said spool-carrier, a raceway plate 90 behind said spool-carrier mechanism, said raceway plates receiving and supporting the studs on said spool-carrier, and mechanism operating between said front and rear raceway plates to cause said studs to traverse the 95 raceway in each of said raceway plates, substantially as described.

28. In a machine of the class described, a hollow shaft, spool-carrier operating disks on said hollow shaft, a gear wheel on said 100 hollow shaft, a journal bearing on said hollow shaft between said gear wheel and said disks to support the rear end of said hollow shaft, a non-rotatable shaft within said hollow shaft to support the front end of said 105 hollow shaft, and a bracket at the rear of said gear wheel engaging and supporting the rear end of said non-rotatable shaft, substantially as set forth.

In testimony whereof I hereunto affix my 110 signature in the presence of two witnesses.

JOHN WINSOR.
